UNITED STATES PATENT OFFICE.

RICHARD FLEMING, OF SWAMPSCOTT, AND CROMWELL A. B. HALVORSON, JR., OF LYNN,
MASSACHUSETTS, ASSIGNEES TO GENERAL ELECTRIC COMPANY, A CORPORATION OF
NEW YORK.

ARC-LAMP.

No. 866,012.

Specification of Letters Patent.

Patented Sept. 17, 1907.

Application filed March 12, 1904, Serial No. 197,827. Renewed April 7, 1906. Serial No. 310,474.

To all whom it may concern:

Be it known that we, RICHARD FLEMING and CROMWELL A. B. HALVORSON, Jr., citizens of the United States, residing, respectively, at Swampscott, county of Essex, State of Massachusetts, and at Lynn, county of Essex, State of Massachusetts, have invented certain new and useful Improvements in Arc-Lamps, of which the following is a specification.

With many materials which may be employed in the composition of arc light electrodes, such for instance as titanium carbide, the arcing end of the electrode may become more or less covered with a film or layer of material formed by the arc which is non-conducting when cold.

15 The object of our present invention is the provision of means for starting an arc from such electrode.

In carrying out our invention we provide means for starting an arc from the side of the electrode some distance below its arcing end and then transferring the arc to the end of the electrode. With a negative electrode giving a flaming or luminous arc a non-consuming positive electrode may be employed, and in the drawings which form a part of the present application we have shown our invention employed in 25 connection with such an electrode.

The various features of novelty which characterize our invention are pointed out with particularity in the claims annexed to and forming a part of this specification.

30 For a better understanding of our invention, however, reference may be made to the accompanying drawings and description in which we have illustrated and described one embodiment of it.

Of the drawings, Figure 1 is a view partly in elevation and partly diagrammatic illustrating an arc lamp equipped with our invention; Fig. 2 is an elevation with parts broken away and in section showing a portion of the mechanism; and Fig. 3 is a similar view showing the parts in a different position.

40 Our invention may be advantageously employed in connection with the lamp shown and described in application for a patent on arc lamps, Serial No. 181,332, filed jointly by us on the 16th day of November, 1903. The mechanism shown in the drawings is 45 substantially the same as that shown in the application aforesaid except as it is modified by the addition of our present invention.

Referring to the drawings, 1 represents a platform forming a part of the lamp frame work. A tubular member 2 forming a part of the draft tube or chimney of the lamp is secured to, and insulated from, the under side of the platform 1 in any suitable manner. Slots 3 are formed near the lower end of the tubular member 2 through which the main positive non-

55 consuming electrode, in the form of an arc shaped bar 4, may pass. The bar 4 is preferably formed of wrought copper. The ends of the bar 4 are clamped between the end of a pair of bow shaped members 5 and 6. The bow shaped members 5 and 6 are pivotally connected to the tubular member 2 at diametrically opposed points by screws 7. The pivotal screws 7 are usually placed substantially in line with the axis about which the outer periphery of the bar 4 is struck.

A member 8 of suitable conducting material such as 65 copper or carbon is carried by the bar 4 near one of its ends. The member 8 may be integrally or rigidly connected to the bar 4 but is preferably pivoted to the bar as shown. The lower end of the member 8 extends somewhat to the right of the body of the 70 member when the parts are in the position shown in Fig. 3.

A projection 6' from the arm 6 is link-connected to a U-shaped armature 9 which with its co-operating winding 10 is mounted above the platform 1. To the 75 under side of the armature 9 is secured one end of the pawl 11 of a clutch 11' which engages a vertical tubular member 12. To the lower end of the tubular member 12, which slides on a suitably supported guide rod 12', is secured an arm 13 which has formed in its free end 80 a socket 14 in which the negative consuming electrode 15 is held in line with the axis of the tubular member 2. The electrode 15 is preferably formed of or contains some substance giving a flaming or luminous arc, such as titanium carbide. When the electrode is formed 85 of titanium carbide it is preferably coated with copper.

When the windings 10 are energized in a manner hereinafter described, the armature 9 will be raised and the clutch 11' will engage the member 12 and move the electrode 15 into engagement with the under side 90 of the arc shaped member 4 which will then be oscillated into the position shown in Fig. 3 by the link connection between it and the armature. When the clutch 11 is in the position shown in Fig. 1 its yoke rests upon the upper surface of a stop 17 adjustably 95 mounted on a rod 18 extending upward from the platform 1, and the member 12 is free to move through it. The pawl 19 of a clutch 20 is normally held in engagement with the member 12 by the action of a spring 20'. When the member 12 is raised the clutch 20 will 100 move upward with the member 12 until the pawl 19 strikes the lower surface of the stop 17, after which the member 12 will move through the yoke of the clutch 20. In the position shown in Fig. 1 the pawl 19 rests against the upper side of a stop 21 also secured to the 105 rod 18.

The circuit arrangements of the lamp and its operation may be better understood from Fig. 1, in which

30 and 31 represent the lamp terminals. A conductor 32 connects the terminal 30 to the electrode 15. One terminal of the windings 10 is also connected to the terminal 30. The other end of the windings 10 is connected to a contact member 33 by a conductor 34. The contact member 33 is carried by an armature 35 pivotally mounted on the core 36 of an electro magnet 37. When the electro magnet 37 is deenergized the contact 33 is in engagement with a contact member 38 but when the electro magnet is energized the contacts are separated. The contact member 38 is connected by a conductor 39 to one terminal of a resistance conductor 40, the outer end of which is connected to the terminal 31.

15 A conductor 41 connects one terminal of a voltage coil 42 with the line 39. The other terminal of the voltage coil 42 is connected to the conductor 34. A conductor 43 connects the lamp terminal 31 with one end of the winding of electro magnet 37. The other end of the winding of the magnet 37 is in electrical connection with a conductor 44 which in turn is in electrical connection with the positive electrode 4 of the lamp.

20 The pivoted armature 45 cooperating with the voltage coil 42 carries a contact 46 which is normally separated from, but is adapted under some circumstances to engage, the contact 47 carried by the core of the magnet. A conductor 48 connects the contact 46 to the line 43. A conductor 49 connects the contact 47 with the lower terminal of the winding of the electro magnet 37.

25 The out-of-service condition of the lamp is shown in Fig. 1. When the lamp terminals are connected to a suitable source, current will begin to flow between the terminals 30 and 31 through the windings 10, conductor 34, contacts 33 and 38, conductor 39 and resistance conductor 40. The passage of current through the windings 10 will cause the armature 9 to be raised. This will move the electrode 15 into contact with the 30 under side of the electrode 4, which at the same time is oscillated into the position shown in Fig. 3. In this position, as is clearly shown in the drawing, the lower end of the swinging member 8 will engage the side of the electrode 15 at a point far enough below its upper 35 end to insure freedom from any layer of non-conducting material formed by the arc. Though the presence of non-conducting material on the end of the electrode 15 may prevent the passage of current directly from the end of the electrode 15 to the bar 4, current can flow 40 between the side of the electrode 15 and the bar 4 through the member 8, which then serves as an auxiliary electrode. Upon contact between the electrode 15, bar 4 and member 8, current will therefore begin to flow between the electrode 15 and member 8 through 45 a circuit which includes conductor 32, electrode 15, member 8, electrode 4, conductor 44, winding of the electro magnet 37 and conductor 43. The passage of current through the winding of the electro magnet 37 will cause the armature 35 to be oscillated and therefore 50 by separate the contacts 33 and 38. When this occurs the winding 10 will be deenergized, the electrode 15 will begin to descend and the member 4 begin to swing back into the position shown in Fig. 2. As the member 8 and electrode 15 separate an arc will be drawn 55 between them which will be transferred from the mem-

ber 8 to the body of the bar 4, as the movement of the separation continues. The heat produced by this arc will very soon cause the end of the electrode 15 to become conducting after which the arc will extend from its upper end. The downward movement of the electrode 15 will be limited by the engagement of the pawl 19 with the stop 21. When sufficiently good contact is made between the end of the electrode 15 and the bar 4 it will of course be understood that the arc may be formed initially between the electrode 15 and the bar 70 4. The voltage coil 42 is so proportioned that for ordinary arc lengths the current passing through its winding will be insufficient to move the armature 45. When however, the voltage of the arc increases to a predetermined maximum, the current passing through the 80 winding 42 will cause the armature 45 to move and bring the contact 46 into engagement with the contact 47. This action throws a low resistance shunt, comprising conductor 48, contacts 46 and 47, and conductor 49, about the winding of the electro magnet 37, 85 whereupon the contact member 33 will move into engagement with the contact member 38, closing the circuit through the winding 10. The electrode 15 will then be again moved into engagement with the under side of the bar 4 after which an arc will again 90 be struck in the manner hereinbefore described. The feeding operation will be repeated whenever the voltage of the arc rises above a predetermined maximum.

95 It will be readily understood that when each feeding action takes place the clutch 20 will move with the tubular member 12 until the pawl 19 strikes the under side of the stop 17, after which the member 12 will be moved through the yoke of the clutch 20 an amount equal to the length of the electrode consumed since the previous feeding operation.

100 While in the drawings and the foregoing description we have illustrated and described one form in which our invention may be embodied we do not intend that the claims annexed to and forming a part of this specification shall be limited to this embodiment more than 105 is made necessary by the state of the art as many changes may be made in the form of our invention without departing from its spirit.

110 What we claim as new and desire to secure by Letters Patent of the United States, is:

1. In an arc lamp, a movable non-consuming electrode, a movable consuming electrode, and a member carried by the non-consuming electrode for engaging said consuming electrode some distance from its arcing end in the feeding operation of the lamp.

115 2. In an arc lamp, a vertical movable consuming electrode, an oscillating non-consuming electrode, and a member carried thereby for engaging the side of said consuming electrode at the same time that the end of the consuming electrode engages the non-consuming electrode.

120 3. In an arc lamp, an electrode comprising a frame provided with a main arcing surface and an auxiliary arcing surface, a second electrode, normally separated from the first mentioned electrode, and means for causing the first-mentioned electrode to engage at its auxiliary arcing 125 surface with the side of the second electrode during the feeding operation of the lamp.

4. In an arc lamp, a movable non-consuming electrode, a pencil shaped consuming electrode from the end of which an arc extends to the non-consuming electrode in 130 the normal operation of the lamp, and a member carried by said non-consuming electrode, and adapted to engage with the consuming electrode some distance below its arcing end in the feeding operation of the lamp.

5. In an arc lamp, a consuming electrode reciprocated in the feeding operation of the lamp, a non-consuming electrode oscillated in the feeding operation of the lamp, and a member carried by said non-consuming electrode 5 adapted to engage the side of said consuming electrode in the feeding operation of the lamp.
6. In an arc lamp, a movable non-consuming electrode, and an auxiliary electrode movably connected thereto.
7. In an arc lamp, a movable non-consuming electrode, 10 and an auxiliary non-consuming electrode movably secured thereto.
8. In an arc lamp, a pivoted non-consuming electrode, and an auxiliary electrode pivoted thereto.
9. In an arc lamp, a movable non-consuming electrode 15 formed out of copper, and an auxiliary copper electrode connected thereto.
10. In combination, a pair of coöperating electrodes, and a side starter carried by one of the electrodes and adapted to engage the other.
11. In an arc lamp, a movable non-consuming electrode, 20 a consuming electrode from the end of which an arc extends to the non-consuming electrode in the normal operation of the lamp, a member carried by the non-consuming electrode, and means for controlling said electrode and said member so as to cause said member to be brought into 25 engagement with the consuming electrode some distance below its arcing end in the feeding operation of the lamp.

In witness whereof, we have hereunto set our hands this tenth day of March 1904.

RICHARD FLEMING.
